Application August 21, 1941, Serial No. 407,771

39 Claims.

(Cl. 223—37)

This invention relates to shirt folding tables and more particularly to a novel method of operation as well as apparatus for carrying out the folding of shirts and like garments in factories or in laundries.

An important object is to provide means for carrying out such folding operation in a more efficient and accurate manner by assuring perfect alignment of the shirt, particularly with reference to its collar and button strip as the shirt is laid or spread upon the table by the operator, then by maintaining this relation of the shirt throughout the folding steps, and thereafter, by releasing and removing the folded shirt, while still on the shirt folding board, in a direction perpendicular from the table to prevent the breaking of the collar as it is withdrawn from the collar former or expander.

Heretofore in the folding of shirts, difficulty has been experienced generally in laying the shirts upon the table so that the center line defined by the button strip will remain in alignment with the collar or neckband as the shirt is folded. Due to the inability to control the accuracy of the operator at the speed required in an operation of this kind, approximation was the general rule followed by the operator in placing the shirt upon the table for folding with the result that generally a very undesirable finished product would be produced. Moreover, the structure heretofore provided required the folded shirt to be removed at an angle from the collar former or expander. Due to the lack of clearance in the recess carrying the collar former and receiving the collar, the rear portion of the collar was forced against the collar former with the result that the pressure against the collar would break the starch and separate the layers of material forming the collar and leaving an undesirable blistering and often a puckering at the collar bands.

The present invention is directed to a structure and method of operation that assure accuracy by the operator as well as increased speed without sacrificing this accuracy, the operator being compelled by the use of ordinary care only to align the button strip forming the center line of the shirt with the collar, and thereafter, without dislodging the same, complete the folding, so that a shirt folded in the manner herein disclosed presents not only a neater, more attractive and a better finished product, but one which is more comfortable to the customer for wearing purposes, since the collar is kept intact in its natural formed condition by the collar former or ex-

pander and the shirt is folded about the natural center line of the shirt.

This invention is more specifically directed to a novel centering and aligning means and to an actuator that effects expansion of the collar and neckband former and movement of a clamp into shirt gripping position as soon as the button strip of the shirt has been brought into relation with the centering and aligning means. The operation is preferably automatic with respect to the action of the collar former in expanding within the collar of the shirt and the action of the clamp to grip the shirt at the opposite end as the operator spreads the shirt upon the table and brings the button strip in proper centering relation. The action of the collar and neckband former is practically simultaneous with, if not slightly in advance of, the action of the clamp but not before the collar has been adjusted about the collar former by reason of the centering of the button strip before the actuator is engaged by the operator's hand. The period of time for this latter adjustment is slight but necessarily present. The collar former should preferably not expand to lock the collar against movement before adjustment of the collar and centering of the button strip are obtained. Thus, the shirt will be properly positioned before held upon the table and this proper centering will be assured before the collar former and clamp are operated.

Additional advantages may be obtained in a structure of the type disclosed by the provision of novel operating mechanism that will effect a predetermined sequence of operation of the parts.

If so desired, the collar former may be released and moved to contracted position in timed relation to the lifting of the shirt forming board and the operating parts may be thereby conditioned for subsequent folding operation. The arrangement effects contraction of the collar former, however, before the board is lifted, but, in so doing, the operating connection of the collar former is conditioned for actuation into an expanded position when the actuator on the table is again engaged. The operating mechanism will also return the shirt forming board to its original position without further attention by the operator so that his board will be ready for immediate use in the folding of the next shirt.

A further object of the invention resides in the simple form and arrangement of parts, as well as the type of efficient structure provided, that assures exceptional accuracy by the operator and the production of a finished product which is consistently acceptable and of uniform appearance.

A still further object of the invention is to provide a machine of this type that requires a minimum amount of labor by the operator and is capable of relatively rapid operation.

Other objects and advantages of the invention will be apparent from the following detail description taken in connection with the accompanying drawings, which form a part hereof.

In the drawings:

Figure 1 is a perspective view of a shirt folding table embodying the invention;

Fig. 2 is a top plan view of the same;

Fig. 3 is a view of one end of the shirt folding table, the shirt folding board being shown tilted away from the bed of the table and a portion of the pedestal being broken away to illustrate the foot pedal and the air valve which is actuated thereby;

Fig. 4 is an enlarged bottom view of the table to illustrate the air connections adapted to operate the moving parts;

Fig. 5 is an enlarged detail view illustrating the mechanism permitting ready and easy alignment of the button strip after the collar of the shirt is inserted about the collar former, and the actuator which the operator automatically operates while aligning the button strip with this mechanism, this view also showing the clamping device that is actuated to grip the lower portion of the shirt as soon as the operator touches the actuator;

Fig. 6 is a view partly in section and partly in elevation of the structure shown in Fig. 5;

Fig. 7 is an enlarged detail sectional view taken along line 7-7 of Fig. 4 to illustrate the air controlled operating mechanism for the various movable parts;

Fig. 8 is an enlarged sectional view taken on line 8-8 of Fig. 7;

Fig. 9 is a similar view taken along line 9-9 of Fig. 7;

Fig. 10 illustrates a shirt in dotted lines laid upon the table to show the position of certain parts which follow the operation of centering or aligning the button strip;

Fig. 11 is a similar view but with the shirt folded about the shirt folding board; and

Fig. 12 illustrates the shirt folding board and the shirt folded thereon being lifted vertically with respect to the collar former and the bed of the table.

Referring to the drawings, it will be noted that the shirt folding table comprises a suitable support consisting of a bed or body 1 mounted on an adjustable pedestal 2. The height of bed 1 may be varied by adjusting knob 3 which adjusts pedestal 2. The base flares outwardly at the bottom of pedestal 2 and has an opening therein at the front to allow pedal 4 to project forwardly in a position conveniently accessible to the operator.

Near one end of the table, bed 1 is cut away or recessed to provide a cavity 5 shaped to correspond with the collar and neckband of a shirt and as large or slightly larger than the largest size shirt. An expandable collar and neckband former 6 of any suitable type which is expanded into the collar and neckband of the shirt when the latter is spread upon the table is disposed in recess 5. Illustrative of a former that may be used, although it will be understood that any particular former may be employed, a stationary body portion 7 is provided with a bolt 8 passing through an opening in the bed and secured thereto by a nut 9. This stationary body portion

is provided with guideways for a series of movable members, the movement of which along said guideways enables the former to be expanded or contracted, as desired. The expanding portions

5 of the collar and neckband former 6 include a front portion 10 curved to fit the front and side portions of the collar and neckband and a recess 11 in its front to receive the front collar button. This front member of the former has a base or body provided with a T slot to receive a guiding T rib 12 of the base 7 along which member 10 slides (Fig. 8). It also carries one or more depending pins 13, which pass through elongated openings in base 7.

15 The collar and neckband former also includes two rear adjustable members 14 having T slots to receive laterally extending T ribs 15 on base 7, so that said members have lateral movement toward and away from each other on the base. Each of said members is connected by a link 16 (Fig. 10) to the short arm of a bell crank lever 17 pivoted at 18 upon base 7, the longer arms of the two levers 17 having curved slots 19 to receive a pin 20 carried by the front member 10 of the former. The arrangement is such that as the front member 10 is moved back and forth along its guideway on the base 7, it turns the bell crank levers 17 and produces corresponding movement of the two members 14 inwardly and outwardly of the base. Movement of the front portion 10 therefore produces an expanding or contracting movement of all of the movable members of the former.

Depending pins 13 are secured at their lower ends in bracket members 18' and 19', the former being provided with a hole 20' (Fig. 7) through which one end of a rod 21 projects. Rod 21 is provided with a collar 22 forming an abutment to prevent rod 21 from being displaced from slideable movement within this hole 20' in bracket 19'. The opposite end of rod 21 is fixed in a bracket 23 forming part of the framework of the table, and part way along rod 21 is another collar 24 adjustably carried thereon by means of a set screw 25 for varying the pressure of a spring 26 confined on this rod between bracket 18' and collar 24. Bracket 19' is also provided with an operating connection, but, in this instance, this operating connection is in the form 25 of a piston rod 28 fixed in bracket 19' at one end and having piston head 29 at the other end. Piston head 29 operates in an air cylinder 30 adapted to be charged on the opposite side through a hose connection 31. Charging cylinder 30 moves piston head 29 to the left, as viewed in Fig. 7, and compresses spring 26 by moving both brackets 18' and 19' and also pins 13 in the same direction. Such movement of pins 13 causes front member 10 and the two side members 14 of the former to contract and remain contracted as long as cylinder 30 remains charged. Mechanism to be hereinafter described causes the air to bleed from cylinder 30, which causes spring 26 to expand these front and side members of the former when a collar and/or neckband of a shirt is placed thereover in recess 5 and the shirt spread upon the bed, and properly centered or aligned with this collar and/or neckband. It will be understood that whenever the word collar is used or the word neckband is used, the meaning is not to be restricted, because shirts having attached collars may be folded on the machine herein disclosed equally as well as shirts provided with neckbands only.

At or near the other end of bed 1 is one or more transparent windows disposed therein preferably lying flush with the upper surface of the bed or slightly raised therefrom. Two such windows 35 and 36 are shown spaced apart a distance, which, in one of the preferred embodiments of the invention, is equal to the width of the button strip 37 (Fig. 10) along the front of the shirt. This is, of course, not necessary, but has its advantages if adopted. Beneath windows 35 and 36 is an electric lamp 38, or equivalent illuminator, controlled by a source, such as switch 39. An actuator 40 is also disposed in bed 1, but between windows 35 and 36 and in movable relation so that a slight touch by the hand of the operator will depress the same.

The construction of actuator 40 and its mounting will be readily seen in Figs. 5 and 6. It is preferably an elongated bar provided with a depending bracket 41 at the inner end, which, by means of a pin 42, pivotally mounts this bar upon a bracket 43 secured to a frame member 44. Bar 40 also rests upon head 46 of an arm 47 extending to one side so as to be pivotally carried by a pin 48 upon a bracket 49 suitably secured within the body of the table. Arm 47 is in the nature of a link that extends beyond pivot point 48 and through the rear face of the table body and terminates in a threaded enlargement 50. An adjustable member, such as a bolt 51, extends upwardly adjacent a shirt clamp 52.

This shirt clamp 52 is preferably pivoted at 53 to a bracket 54 mounted along the corner edge of one end face of the table, as shown in Fig. 1, the clamp 52 being of gooseneck shape so that its free front end 55 extends at an angle to lay in front of windows 35 and 36 and actuator 40 but without interfering, when it drops about its pivot 53 to shirt gripping position, with the hand of the operator centering the button strip 37 between windows 35 and 36, as shown in Fig. 10. An over-center acting spring 56 causes clamp 52 to drop into its shirt gripping position when a projection 57 thereon is thrown up by the tilting movement of bolt 51 carried on link 47, engageable by actuator 40. This spring 56 moreover functions to hold clamp 52 in its vertical position as shown in dotted lines in Fig. 6, when the clamp is manually lifted to such position from its shirt engaging position.

A depending arm 60 is carried by bracket 41 secured to the underside of actuator 40. The lower end of arm 60 is adapted to engage a pin 61 carrying an exhaust valve 62 lying in an air cylinder 63 mounted in the lower end of bracket 44. A spring 64 normally keeps valve 62 seated while a spring 65 normally keeps depending arm 60 in non-actuable position. By a suitable nipple connection, air cylinder 63 connects with an air line 66 leading to a T connection 67 which communicates also with air line 31 and an air supply pipe 68, a check valve 69 being interposed between air lines 31 and 66 and supply pipe 68 to permit the air to flow in one direction only into air lines 31 and 66. It will be observed that actuator 40 is mounted to lie slightly raised or in extended position with respect to the top surface of the table or bed 1 and that it is so positioned that it will readily tilt downwardly about pivotal mounting 42. The arrangement may vary and the parts may be so proportioned that the slightest touch by the hand of the operator, as she moves her hand across the bed 1 when bringing the button strip 37 into centering position between transparent windows 35 and 36, will

cause actuator to be depressed sufficiently to actuate clamp 52 into shirt gripping position, as shown in Fig. 6, by raising bolt 51 and flipping the clamp far enough about its pivot 53 to cause the over-center acting spring 56 to complete the movement and hold the clamp firmly against the shirt. Actuator 40 will also, when thus depressed, engage pin 61 and move it inwardly to unseat valve 62 and bleed air lines 66 and 31 and air cylinder 30.

Reducing the air pressure in cylinder 30 allows spring 26 to move pins 13 of the collar and neckband former to the right and expand the front member 10 and the two rear adjustable members 14 of the former. It will be noted, therefore, that this former is adapted to expand within the neckband and collar of the shirt as the latter is being spread and centered upon bed 1, the arrangement novelly permitting the former to expand approximately at the same time or slightly in advance of clamp 52 dropping into position to grip the shirt. Whether the former 6 expands simultaneously with or slightly in advance of clamp 52 gripping the shirt is a matter of choice but it is found that the work of the operator in spreading and centering the shirt upon bed 1 is facilitated and accuracy made more certain if the operating parts described causes depending arm 60 to unseat exhaust valve 62 and exhaust the air in air lines 31 and 66 before lever arm 47 completes its movement to lift bolt 51 sufficiently to throw clamp 52 and for spring 56 to complete the swinging movement of clamp 52. Thus, former 6 may be expanded sufficiently in advance of the action of clamp 52 to assure that the button strip 37 of the shirt has been straightened and pulled taut before clamp 52 grips the shirt near the tail end, as illustrated in Fig. 10.

It is further pointed out that the novel arrangement of the parts thus far described has for an additional advantage a tendency to aid the operator in the work of centering a shirt and assure that accuracy is obtained. The shirt is laid with the front thereof upon bed 1 and the collar or neckband is inserted in recess 5 about the front and rear members 10 and 14 of former 6. At this time, former 6 is in its contracted position, as shown in Fig. 2, and clamp 52 is raised. As the operator spreads the shirt upon bed 1 and grips the button strip 37 to bring the lower end thereof between transparent windows 35 and 36, there is a tendency for the shirt to pivot or swing about former 6 with the collar moving and adjusting itself about this former so that when the lower end of button strip 37 is brought between windows 35 and 36, the entire shirt has been properly centered whereupon contact with actuator 40 instantly expands the former and holds the shirt at the collar or neckband end so that the operator may continue in pulling the shirt taut as clamp 52 is caused to swing downwardly into shirt gripping position. The action of these operating parts may be made rapid so that to the eye it would appear that both the former 6 and the clamp 52 operate immediately upon contact with actuator 40.

Adjacent the collar and neckband opening 5 and near the end of bed 1 is a vertically movable carriage designated broadly as 75, to which is pivotally attached a shirt folding board 76. Carriage 75 is adapted to move up and down in a plane perpendicular to bed 1 and shirt folding board 76 is also adapted to pivotally move with respect to the carriage after this board is moved

to the dotted line position shown in Fig. 7. Carriage 75 comprises rods 77 and 78 secured to movable end posts 79 and 80. Each post is provided at its lower end with a rod 81 extending into an air chamber 82 and having a piston head 83 at its lower end. Each air cylinder 82 may be suitably carried by the framework of the table. In this connection, brackets 84 may be provided and carried by a plate 85 forming part of frame member 86. The upper end of each cylinder may have a tightly fitted cap 87 driven thereinto and through which rod 81 moves. The lower end of each cylinder 82 may receive a fitting 88 into which air lines 89 are threaded and connect by a single pipe 90 to an air release valve 91 controlling the air supply to cylinders 82 by air supply pipes 68. Upward movement of end posts 79 and 80 is determined by the length of a sleeve 92 disposed about rod 81. Air entering cylinders 82 lifts piston heads 83 against the tension of springs 93 in cylinders 82, which springs 93 function to lower the piston heads 83 when air is exhausted from cylinders 82, and to cushion the upward movement of piston heads against shock.

At the opposite ends of lower rod 78 of carriage 75 sleeves 94 are pivotally mounted to carry brackets 95 into which rods 96 are threaded for supporting counterweights 97. Substantially flat plate-like brackets 98 are disposed on the sleeves 94 opposite brackets 95 and the shirt folding board 76 may be secured to brackets 98 by rivets or other suitable means. When carriage 75 has been raised, shirt folding board 76 may be swung upon its pivotal mounting comprising the bracket sleeves 94 on said lower rod 78 to its raised position, as shown in Figs. 2 and 3. The counterweights 97 function to hold board 76 in its raised position until the next folding operation.

Any suitable type of clamp 100 may be employed adjacent the hinged end of the shirt folding board 76 for the purpose of holding the folded-over portions of the shirt adjacent the collar while the tail of the shirt is being folded upwardly and over the end of this folding board. If this clamp is carried upon board 76, its U-shaped mounting bracket 101 may be mounted upon board 76 instead of bed 1 directly behind rods 77 and 78 of carriage 75. By also making clamp 100 transversely of U-shaped formation so that its sides extend downwardly to pivot upon the upstanding ears of bracket 101, an interior space within is provided to receive an over-center acting spring 102, one end of this spring being secured at 103 to the underside of the clamp at its top and the other end of the spring being secured at 104 to the horizontal leg of bracket 101. By reason of the clamp's dimensions and the location of the securement of this spring, the latter will cause the clamp to remain both in its operative and inoperative positions under the tension of said spring. Turning of the clamp about its pivot causes it to snap into position and be retained in that position until it is turned in the opposite direction. It is preferable that the clamp engage symmetrically along the longitudinal center line of board 76. When the sides of the shirt are successively folded over the longitudinal edges of the board, which is after the shirt has been centered and locked upon bed 1 by the expansion of the neckband former and movement of clamp 52 into operative position and each sleeve is folded to extend longitudinally of the board, the operator snaps clamp 100 about its pivot to mechanically hold the neckband and shoulder portions whereby to leave the hands of

the operator free to tightly and transversely draw the midportions of the shirt about the board and to then fold upwardly over the lower edge the tail portion of the shirt. Clamp 100 may be then slightly raised and the tail end of the shirt slipped thereunder, after which this clamp is returned to its full operative position for holding the tail as well as the previously mentioned portions of the shirt. Both hands of the operator are now free to band the shirt by means of bands lying in a transversely extending channel or pocket 106 disposed in bed 1. The floor 107 of channel 106 is provided with transverse slots 108 to receive spring-pressed screws 109 extending upwardly through these slots into a movable adjusting block 110. The distance a between inside face 111 and block 110 indicates the width of the band that may be used. Hence, any width of band may be employed by adjusting block 110.

The air release valve 91 in air line 90 between air supply pipe 68 and air cylinders 82 of the vertically moving carriage 75 carrying the shirt folding board 76 includes an assembly comprising valve 112 operating against a spring 113. Stem 114 is of smaller diameter than passage 115 in which it moves. A groove 116 extends centrally of valve 112 and into stem 114 and communicates with a transverse passage 116', as shown in Fig. 7, so that the air supplied to air line 90 and air cylinders 82 to raise carriage 75 may slowly bleed back into line 68 and exhaust into atmosphere at valve 117. Valve 115 may be of conventional design that will connect pipe 118 with pipe 68 when pedal 4 is depressed. When pedal 4 is again allowed to return to its normal position, valve 117 will connect pipe 68 to a port exhausting to atmosphere. In this manner, carriage 75 is automatically permitted to return to its lower position after the foot pedal 4 is actuated and the folded shirt removed from board 76.

It will be observed that brackets 95 carrying rods 96 and their counterbalancing weights 97 are cut away at 130 to engage against upper rod 77 whereby to hold shirt folding board 76 at all times in a plane parallel to bed 1 when this board is swung to its lower position, as shown in Fig. 1. Board 76 will remain in this relation to bed 1 during the lifting movement of carriage 75. It will therefore be apparent that the collar or neckband of the folded shirt upon board 76 will be lifted directly vertical with respect to members 10 and 14 of the former without being pressed thereagainst, say, against the rear members 14, to break the starch and separate the layers of material forming the collar. In Fig. 7, the upper position of shirt folding board 76 before it is swung to its tilted position about its pivotal mounting upon lower rod 78 is shown in dotted lines. In this upper position, board 76 still remains parallel to bed 1. To assist in removing the collar or the neckband of the folded shirt from the former 6 when carriage 75 is raised and board 76 is lifted with the folded shirt thereon, I preferably proportion piston head 29 and air cylinder 30 with respect to the piston heads 83 and air cylinders 82 to cause piston head 29 to operate in advance of the piston heads 83. Hence, the former 6 may be contracted slightly in advance of the raising movement of carriage 75 and board 76, so that this former is contracted before the collar is withdrawn therefrom in a vertical direction. There is, therefore, no opportunity for the collar to crush or break. A further important advantage in raising board 76 in a horizontal position by the vertical movement of

carriage 75 is the fact that the operator is permitted to slip the folded shirt in a horizontal direction from this board when in its dotted line position shown in Fig. 7. Movement of the operator's hands in a horizontal direction is a natural movement and is less fatiguing than in a vertical direction which was heretofore required when the shirt folding board merely pivoted back when lifting the folded shirt from the collar and neckband former.

The operation of the apparatus is as follows: When a shirt is applied face down on the table or bed 1 and the neckband or collar is inserted in recess 5 about the members 10 and 14 of the former 6, the latter will be in contracted position by reason of the preceding operation of depressing pedal 4, which charges air cylinder 30 to contract these members 10 and 14 against the tension of spring 26. The collar or neckband is thus extending downwardly through opening 5 in bed 1 and the shirt is pivoted at the collar or neckband about said members 10 and 14 until it is centered and the operator brings the tail end of the button strip 37 in alignment between transparent windows 35 and 36. In so doing, the operator's hand will contact actuator 40 and depress it whereby the collar or neckband former 6 will immediately expand to permit the operator to pull the button strip 37 taut as the clamp 52 is swung into shirt gripping position, as shown in Fig. 10. The operation between the former 6 and the clamp 52 may be timed to permit the former 6 to expand momentarily before clamp 52 is dropped into its operative position to grip the shirt.

The usual cardboard stiffener may then be inserted in clips 120 projecting from the underside of the shirt folding board 76 and this board swung downwardly so that the stiffener is between the shirt and the folding board. The sides of the shirt are successively folded over the longitudinal edges of the folding board with each sleeve folded to extend longitudinally of the board. When the shirt is thus folded, the operator snaps the clamp 100 about its pivots to hold the shoulder portions and leave the hands of the operator free to tightly and transversely draw the midportion of the shirt about the board adjacent the end thereof and to then fold upwardly over said end edge the tail portion and cuffs of the shirt, the clamp 52 being flipped back to upper position to release the tail of the shirt adjacent the windows 35 and 36 during this operation. A band from the band magazine 106 may then be applied about the folded shirt.

The operator may then lift clamp 100 to its inoperative position and step upon foot pedal 4 to cause air to flow through air lines 31 and 90. This step in the operation will immediately cause the former 6 to contract and momentarily thereafter cause carriage 75 to move upwardly whereby to raise the shirt folding board 76 in a vertical direction but in a plane at all times parallel to bed 1. When this board 76 moves to its upper position, as shown in dotted lines in Fig. 7, the operator removes the folded shirt by slipping it outwardly from the free end of the board by a horizontal movement of her hands. This board is then tilted backwardly to the position shown in Figs. 2 and 3. When pedal 4 is released, air will slowly exhaust from air cylinders 82 through air release valve 91 and exhaust to atmosphere at valve 117. This will cause carriage 75 to move to its lower position for the next folding opera-

tion. During the period between folding operations, air cylinder 30 will remain charged and keep the collar and neckband former contracted.

From the foregoing description, it will be apparent that I have provided certain improvements in a shirt folding table that permits the folding of a shirt to be more scientifically and accurately performed in a natural sequence of steps, the folded shirt presenting a neater, more attractive and better finished product which is more comfortable to the customer for wearing purposes because the collar has been set and the shirt folded immediately after ironing along a natural center line. After the shirt has been spread and centered upon bed 1, it is firmly held in this relation while the sides of the shirt are folded over the board so that it is impossible for any shifting before the folding steps are completed.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. A shirt folding table including a shirt receiving bed provided with a recess, an expandable neckband former in said recess, a board disposed above said bed and over which the edges of the shirt are folded, and means to raise and lower said board in a perpendicular direction with respect to said expandable neckband former and thereby keep said board during its movement toward and away from said former in a plane parallel to said bed.

2. A shirt folding table including a shirt receiving bed provided with a recess, an expandable neckband former in said recess, a board disposed above said bed and over which the edges of the shirt are folded, a carriage for supporting said board, and means to raise and lower said carriage the movement of said carriage moving said board perpendicularly with respect to said expandable neckband former whereby to keep the same said board substantially parallel to said bed in its movement toward and away from said former.

3. A shirt folding table including a shirt receiving bed provided with a recess, an expandable neckband former in said recess, a board disposed above said bed and over which the edges of the shirt are folded, a carriage for supporting said board, said bed having an opening through which said carriage extends, and means for moving said carriage vertically through said opening.

4. A shirt folding table including a shirt receiving bed provided with a recess, a neckband former in said recess, a board disposed above said bed and over which the edges of the shirt are folded, a carriage for supporting said board, said bed having an opening through which said carriage extends, and air controlled means for operating said carriage, the support for said board on said carriage being so constructed and arranged that the movement of said carriage automatically lifts said board vertically with respect to said neckband former.

5. A shirt folding table including a shirt receiving bed provided with a recess, a collar and neckband former in said recess, a board disposed

above said bed and over which the edges of the shirt are folded; a carriage for supporting said board, said bed having an opening through which said carriage extends, air controlled means for operating said carriage and lifting said board vertically with respect to said former, and automatic bleeding means for releasing the air pressure actuating said carriage to return said board to its lower position after a predetermined period.

5. 6. A shirt folding table including a shirt receiving bed provided with a recess, a collar and neckband former in said recess, a board disposed above said bed and over which the edges of the shirt are folded, a mounting for said board, and means for movably supporting said mounting with respect to said bed and for moving said board vertically away from over said former in its movement to lift the collar of the shirt from said former.

7. A shirt folding table including a shirt receiving bed provided with a recess, an expandible collar and a neckband former in said recess, a board disposed above said former and over which the edges of the shirt are folded, a carriage for supporting said board, means for movably supporting said carriage with respect to said bed the support for said board on said carriage being so constructed and arranged that the movement of said carriage moves said board vertically away from over said former, and means for expanding said former when receiving a collar or neckband of a shirt and for contracting said former when the same is removed, both of said means including mechanism for effecting contraction of said former to release the collar or neckband therefrom prior to the vertical movement of said board to move the shirt folded thereon away from said bed.

8. A shirt folding table including a shirt receiving bed provided with a recess, an expandible collar and neckband former in said recess, a board disposed above said former and over which the edges of the shirt are folded, a carriage for supporting said board, means for contracting and expanding said former, means for moving said carriage and said board vertically away from said former, and means for effecting said last two operations in a predetermined sequence whereby said former will first contract and said board will then be lifted vertically away from said former.

9. A shirt folding table including a shirt receiving bed provided with a recess, an expandible collar and neckband former in said recess, a board disposed above said former and over which the edges of the shirt are folded, a carriage for supporting said board, means for expanding and contracting said former, means for vertically moving said carriage to move said board vertically away from said former, each of said means including an air chamber for effecting the actuating movement and a spring for effecting the return movement, a source of air supply, and means to control the flow of air supplied to each of said air chambers.

10. A shirt folding table including a shirt receiving bed provided with a recess, an expandible collar and neckband former in said recess, a board disposed above said former and over which the edges of the shirt are folded, a carriage for supporting said board, means for expanding and contracting said former, means for vertically moving said carriage to move said board vertically away from said former, each of said means including an air chamber for effecting the actu-

ating movement and a spring for effecting the return movement, a source of air supply, and means to control the flow of air supplied to each of said air chambers, the air chamber effecting the actuating movement of said former being of larger cross-sectional area than the air chamber effecting the actuating movement of said carriage whereby to initiate the actuation of said former prior to any actuating movement of said carriage.

11. A shirt folding table including a shirt receiving bed provided with a recess, an expandible collar and neckband former in said recess, a board disposed above said former and over which the edges of the shirt are folded, a carriage for supporting said board, means for expanding and contracting said former, means for vertically moving said carriage to move said board vertically away from said former, each of said means including an air chamber for effecting the actuating movement and a spring for effecting the return movement, a source of air supply, means to control the flow of air supplied to each of said air chambers, the air chamber effecting the actuating movement of said former being of larger cross-sectional area than the air chamber effecting the actuating movement of said carriage whereby to initiate the actuation of said former prior to any actuating movement of said carriage, and means for thereafter bleeding the air chamber actuating said carriage to return the same to its original position while said former remains in its actuated position.

12. A shirt folding table including a shirt receiving bed provided with a recess, an expandible collar and neckband former in said recess, shirt centering and aligning means at the opposite end of said bed, said means indicating the position of the button strip of the shirt with respect to its collar positioned about said former, and an actuator adapted for operation by contact with the hand of the operator in centering the shirt by said indicating means to effect expansion of said former.

13. A shirt folding table including a shirt receiving bed provided with a recess, an expandible collar and neckband former in said recess, shirt centering and aligning means at the opposite end of said bed, said means indicating the position of the button strip of the shirt with respect to its collar positioned about said former, a clamp to hold the shirt adjacent said means after it is spread upon said bed and the button strip is properly centered or aligned with the collar, and an actuator adapted for operation by contact with the hand of the operator in centering the shirt, said actuator effecting actuation of said clamp to engage the shirt and effecting an expansion movement of said former.

14. A shirt folding table including a shirt receiving bed provided with a recess, an expandible collar and neckband former in said recess, shirt centering and aligning means at the opposite end of said bed, a clamp for gripping the shirt at said end of the bed, and an actuator adapted to effect expansion of said former and actuation of said clamp.

15. A shirt folding table including a shirt receiving bed, shirt centering and aligning means at one end of said bed, a clamp for gripping the shirt at said end of the bed, and an actuator engageable by the hand of the operator in centering the shirt by said means for actuating said clamp.

16. A shirt folding table including a shirt re-

ceiving bed, shirt centering and aligning means at one end of said bed, a clamp for gripping the shirt at said end of the bed, an actuator engageable by the hand of the operator in centering the shirt by said means for actuating said clamp, and means for holding said clamp in gripping position independently of said actuator.

17. A shirt folding table including a shirt receiving bed, shirt centering and aligning means at one end of said bed, a clamp for gripping the shirt at said end of the bed, an actuator engageable by the hand of the operator in centering the shirt by said means for actuating said clamp, and means for holding said clamp in gripping position independently of said actuator, said clamp being returnable to its open position by manual operation.

18. A shirt folding table including a shirt receiving bed, an expansible collar and neckband former at one end of said bed, shirt centering and aligning means at the opposite end of said bed, a clamp for gripping the shirt at said opposite end of said bed, an actuator engageable by the hand of the operator when centering the shirt for actuating said former to expand the same and for actuating said clamp into shirt gripping position, a board disposed above said former and over which the edges of the shirt are folded, a carriage for said board, said carriage being movable to raise and lower said board perpendicularly with respect to said former, and operating mechanism including pedal means and connections extending to said operating parts for actuating said former to contracted position and for causing said carriage to raise said board perpendicularly with respect to said former.

19. A shirt folding table including a shirt receiving bed, an expansible collar and neckband former at one end of said bed, shirt centering and aligning means at the opposite end of said bed, a clamp for gripping the shirt at said opposite end of said bed, an actuator engageable by the hand of the operator when centering the shirt for actuating said former to expand the same and for actuating said clamp into shirt gripping position, a board disposed above said former and over which the edges of the shirt are folded, a carriage for said board, said carriage being movable to raise and lower said board perpendicularly with respect to said former, and operating mechanism including connections extending to said operating parts for actuating said former to contracted position and for causing said carriage to raise said board perpendicularly with respect to said former.

20. A shirt folding table including a shirt receiving bed, an expansible collar and neckband former carried by said bed, a shirt centering and aligning means also carried by said bed, a clamp for gripping the shirt as it is centered and aligned, an actuator adapted to be operated to expand said former and to move said clamp into shirt gripping position, a board disposed above said former and over which the edges of the shirt are folded, a carriage for said board, said carriage being movable to raise and lower said board perpendicularly with respect to said former, and operating mechanism including connections to said operating parts for actuating said former to contracted position and for causing said carriage to raise said board perpendicularly with respect to said former.

21. A shirt folding table including a shirt receiving bed, an expansible collar and neckband former carried by said bed, a shirt centering and

aligning means also carried by said bed, a clamp for gripping the shirt as it is centered and aligned, an actuator adapted to be operated to expand said former and to move said clamp into shirt gripping position, a board disposed above said former and over which the edges of the shirt are folded, a carriage for said board, said carriage being movable to raise and lower said board perpendicularly with respect to said former, and operating mechanism including connections extending to said operating parts and a lever adapted to be operated after the shirt is folded to contract said former and actuate said carriage to lift said board.

22. A shirt folding table including a shirt receiving bed, an expansible collar and neckband former carried by said bed, a shirt centering and aligning means also carried by said bed, a clamp for gripping the shirt as it is centered and aligned, an actuator adapted to be operated to expand said former and to move said clamp into shirt gripping position, a board disposed above said former and over which the edges of the shirt are folded, a carriage for said board, said carriage being movable to raise and lower said board perpendicularly with respect to said former, and operating mechanism including connections extending to said operating parts and a lever adapted to be operated after said shirt is folded, said connections comprising a source of air supply, air lines extending from said source of air supply to said carriage, said former and to said actuator, and a mechanical connection between said actuator and said clamp, said actuator when operated causing the air to bleed from the line leading to said former to release the same so as to permit it to move to expanded position, said lever when actuated causing the lines leading to said former and said carriage to be charged whereby to contract said former and to lift said carriage.

23. A shirt folding table including a shirt receiving bed, an expansible collar and neckband former carried by said bed, a shirt centering and aligning means also carried by said bed, an actuator adapted to be operated to actuate said former, a board disposed above said former and over which the edges of the shirt are folded, a carriage for said board, said carriage being movable to raise and lower said board, and operating mechanism including connections extending to said operating parts and a lever adapted to be actuated, said connections comprising a source of air supply, air lines extending from said source of air supply to said carriage, said former and to said actuator, said actuator when actuated causing the air to bleed from the line leading to said former, said lever when actuated causing the lines leading to said former and said carriage to be charged.

24. A shirt folding table including a shirt receiving bed, an expansible collar and neckband former carried by said bed, a shirt centering and aligning means also carried by said bed, said bed having a recess therein adjacent said shirt centering and aligning means, an actuator disposed in said recess and extending above said bed adapted to be engaged and depressed, and a connection between said former and said actuator for operating said former when said actuator is depressed.

25. A shirt folding table including a shirt receiving bed, an expansible collar and neckband former carried by said bed, a shirt centering and aligning means also carried by said bed, said

means comprising a pair of spaced apart windows in said bed between which the button strip of the shirt is laid to center and align the shirt after its collar is placed upon said former, and an actuator movably embedded in said bed between said windows for operating said former when engaged during the centering and aligning of the shirt.

26. A shirt folding table including a shirt receiving bed, an expansible collar and neckband former carried by said bed, a shirt centering and aligning means also carried by bed, said means comprising a pair of spaced apart windows in said bed between which the button strip of the shirt is laid to center and align the shirt after its collar is placed upon said former, an actuator movably embedded in said bed between said windows adapted to be actuated during the centering and aligning of the shirt, a clamp for gripping the shirt as it is centered and aligned, and a connection between actuator and said clamp for swinging said clamp into shirt gripping position when said actuator is actuated.

27. A shirt folding table including a shirt receiving bed, a pivotally tilttable clamp movable to shirt gripping position at one end of said bed to engage and grip a shirt, a pivotally mounted bracket engaging said clamp to tilt the same to shirt gripping position, and a pivotally mounted actuator engaging said bracket to actuate said bracket.

28. A shirt folding table including a shirt receiving bed, a pivotally tilttable clamp movable to shirt gripping position at one end of said bed, a pivotally mounted bracket engaging said clamp to tilt the same to shirt gripping position, and an actuator operable manually by the operator in spreading the shirt upon said bed for actuating said bracket.

29. A shirt folding table including a shirt receiving bed, a pivotally tilttable clamp movable to shirt gripping position at one of said bed to engage and grip a shirt, a bracket engaging said clamp to tilt the same to shirt gripping position, and a pivotally mounted actuator engaging said bracket to actuate said bracket.

30. A shirt folding table including a shirt receiving bed, a tilttable clamp movable to shirt gripping position upon said bed, a bracket engaging said clamp to tilt the same to shirt gripping position, and an actuator operable manually by the operator in spreading the shirt upon said bed for actuating said bracket.

31. A shirt folding table including a shirt receiving bed, a pivotally mounted clamp, an over-center spring for holding said clamp in shirt gripping position or in open position, an arm adapted when actuated to engage said clamp to tilt the same and cause said over-center spring to complete the movement of said clamp by a snap action, said arm having an adjustable portion to determine the amount of movement of said arm necessary to cause tilting of said clamp, and an actuator for operating said arm, the amount of movement of said arm to cause tilting of said clamp determining the sensitiveness of said actuator.

32. A shirt folding table including a shirt receiving bed, shirt centering and aligning means at one end of said bed, a pivotally mounted clamp, an over-center spring for holding said clamp in shirt gripping position, an arm adapted when actuated to engage said clamp to tilt the same and cause said over-center spring to complete the movement of said clamp by a snap ac-

tion, said arm having an adjustable portion to determine the amount of movement of said arm necessary to cause tilting of said clamp, and an actuator embedded in said bed and positioned to be engageable by the hand of the operator in centering said shirt by said centering and aligning means for operating said arm, the amount of movement of said arm to cause tilting of said clamp determining the sensitiveness of said actuator.

33. A shirt folding table including a shirt receiving bed, an expansible collar and neckband former carried by said bed, a clamp for gripping the shirt at its tail end, an actuator adapted to be operated to actuate said former and to move said clamp into shirt gripping position, a board over which the edges of the shirt are folded, a carriage for said board, and operating mechanism including connections extending to said operating parts for operating the same including means to contract said former after the shirt is folded and to actuate said carriage to lift said board away from said former.

34. A shirt folding table including a shirt receiving bed, an expansible collar and neckband former carried by said bed, a shirt centering and aligning means also carried by said bed, a clamp for gripping the shirt as it is centered and aligned, a movable board over which the edges of the shirt are folded, an actuator adapted to be operated to expand said former and to move said clamp into shirt gripping position, and operating mechanism including connections extending to said operating parts for operating the same and means to lift said board away from said former.

35. A shirt folding table including a shirt receiving bed, an expansible collar and neckband former carried by said bed, a shirt centering and aligning means also carried by said bed, a clamp for gripping the shirt as it is centered and aligned, a movable board over which the edges of the shirt are folded, an actuator adapted to be operated to expand said former and to move said clamp into shirt gripping position, and operating mechanism including connections extending to said operating parts for operating the same and means to lift said board away from said former and simultaneously to contract said former.

36. A shirt folding table, comprising a frame having a stationary top provided with a surface on which a shirt may be arranged for folding, said table top being provided with a recess in said top surface to receive the neckband portion of a shirt lying face down upon the table and with a light transmitting means spaced from said recess, said means comprising a pair of spaced-apart windows in said table top between which the button strip of the shirt is laid to center and align the shirt on the table top after its collar is placed in said recess, a light source for illuminating said means, a folding blade movably connected with said table top for raising and lowering movement toward and away from a shirt lying upon it, said blade having smooth side edges so that a shirt folded about said blade may be easily removed, the side edges of said blade when in lowered position being symmetrically disposed on either side of the center line connecting said recess and said means.

37. A shirt folding table, comprising a frame having a stationary top provided with a surface on which a shirt may be arranged for folding, said table top being provided with a recess in said top surface to receive the neckband portion

of a shirt lying face down upon the table and with a light transmitting means spaced from said recess, said means comprising a pair of spaced-apart narrow elongated windows in said table top between which and parallel thereto the button strip of the shirt is laid to center and align the shirt on the table top after the collar is placed in said recess, a light source for illuminating said means, a folding blade movably connected with said table top for raising and lowering movement toward and away from a shirt lying upon it, said blade having smooth side edges so that a shirt folded about said blade may be easily removed, the side edges of said blade when in lowered position being symmetrically disposed on either side of the center line connecting said recess and said means.

38. A shirt folding table including a shirt receiving bed, an expandible collar and neckband former carried by said bed, a shirt centering

5 and aligning means also carried by said bed and spaced from said neckband former, said means comprising a pair of spaced-apart windows in said bed between which the button strip of the shirt is laid to center and align the shirt after its collar is placed upon said former, and a light source for illuminating said windows.

39. A shirt folding table including a shirt receiving bed, an expandible collar and neckband former carried by said bed, a shirt centering and aligning means also carried by said bed and spaced from said neckband former, said means comprising a pair of spaced-apart narrow elongated windows in said bed between which the button strip of the shirt is laid to center and align the shirt after its collar is placed upon said former, and a light source for illuminating said windows.

ROY J. RIECK.

CERTIFICATE OF CORRECTION.

Patent No. 2,369,607.

February 13, 1945.

ROY J. RIECK.

It is hereby certified that error appears in the printed specification of the above numbered patent requiring correction as follows: Page 4, second column, line 32, for "Valve 115" read --Valve 117--; page 5, second column, line 49, claim 2, strike out the words "the same"; and that the said Letters Patent should be read with this correction therein that the same may conform to the record of the case in the Patent Office.

Signed and sealed this 5th day of June, A. D. 1945.

Leslie Frazer
